UNITED STATES PATENT OFFICE.

LOUIS H. HANDELL, OF AURORA, ILLINOIS.

TOP.

1,171,196.

Specification of Letters Patent.

Patented Feb. 8, 1916.

Application filed May 29, 1915. Serial No. 31,286.

To all whom it may concern:

Be it known that I, LOUIS H. HANDELL, a citizen of the United States, and a resident of the city of Aurora, county of Kane, and 5 State of Illinois, have invented certain new and useful Improvements in Tops, of which the following is a specification.

My invention relates to improvements in tops, and has for its object an improved device of simple construction which will spin 10 for a long time, and which is capable of emitting sound during the spinning.

The invention consists in the combinations and arrangements of parts hereinafter 15 described and claimed.

The invention will be best understood by reference to the accompanying drawing forming a part of this specification, and in which,

20. Figure 1 is a top plan view of a top embodying my invention, and Fig. 2, a vertical medial section of the same.

The preferred form of construction, as 25 illustrated in the drawing comprises a top body 3 in the form of a hollow cone of substantially sixty-five degrees spinning upon the point thereof. The body 3 is provided with an upwardly extending central integral stem 4 having a spinning socket 5 in 30 its top adapted to receive the point of a nail 6 or other similar instrument. In spinning the top a string 7 is wound about the upper portion of stem 4, above the top body 3, a nail 6 is inserted in socket 5 and the top 35 held in upright position by means of said nail with the point of the body 3 resting upon the spinning surface. Then the string 7 is readily withdrawn from stem 4 imparting a high rotation thereto and to the top 40 body, stem 4 rotating with reference to nail 6 to permit of this. Then the nail is removed and the top permitted to spin under the momentum thus imparted. I found that 45 a top constructed as specified will spin for a long time, and that the best results are obtained by the use of a conical body having an angle of substantially sixty-five degrees.

Tubes 8 are extended through the walls or body 7, being open at their outer ends and

provided with sounding reeds 9 at their 50 inner ends, air being forced through said tubes by the rapid rotation of the top body thus vibrating the reeds 9 to emit sound, which feature adds to the attractiveness of the top as a toy.

While I have illustrated and described the preferred form of construction for carrying my invention into effect, this is capable of variation and modification without departing from the spirit of the invention. I, 60 therefore, do not wish to be limited to the precise details of construction set forth, but desire to avail myself of such variations and modifications as come within the scope of the appended claims.

Having described my invention what I claim as new and desire to secure by Letters Patent is:

1. A top in the form of a hollow cone 70 spinning upon the point thereof, said cone being provided with a central stem extending above it and having a spinning socket in its top; and sound producing agencies on the periphery thereof, substantially as described.

2. A top in the form of a hollow cone of substantially sixty-five degrees spinning upon the point thereof, said cone being provided with a central stem extending above it and having a spinning socket in its top; 80 and sound producing agencies on the periphery thereof, substantially as described.

3. A top in the form of a hollow cone spinning upon the point thereof, said cone being provided with a central stem extending above it and having a spinning socket in its top; and tubes extending through the walls of said cone substantially tangentially thereto, said tubes being open at their outer ends and provided with reeds at their inner 90 ends, substantially as described.

In testimony whereof I have signed my name to this specification in the presence of two subscribing witnesses.

LOUIS H. HANDELL.

Witnesses:

ARTHUR A. OLSON,
HELEN F. LILLIS.
